UNITED STATES PATENT OFFICE

ROY F. ENSIGN, OF LOS ANGELES, CALIFORNIA

WELL-FILLING MEANS FOR CARBURETORS

Application filed August 18, 1926. Serial No. 129,871.

This invention has to do with carburetors and particularly with an arrangement for causing quick filling of an accelerating well after the well has been emptied.

Accelerating wells of various kinds are now in common use in carburetors, and in some instances difficulties have been encountered in causing the filling of the well, as such filling has a tendency to rob the fuel nozzle of fuel and thus to cause uneven operation of the carburetor and of the engine to which the carburetor is attached.

It is a general object of this invention to provide an arrangement whereby such an accelerating well may be filled without robbing the fuel nozzle of fuel necessary for engine operation. How this is done will be best understood from the following detailed description, wherein I explain a simple form of my device, as illustrative of the invention, reference for this purpose being had to the accompanying diagrammatic drawings, in which:

Fig. 1 is a vertical central section of a carburetor equipped with my device, showing the condition assumed in normal or low speed operation;

Fig. 2 is a similar section showing conditions when the throttle has been opened for sudden acceleration; and

Fig. 3 is a similar view showing the conditions after the throttle has again been closed.

It will be understood that the drawings herewith are merely diagrammatic and are not intended to show many practical details of structure and assembly which enter into such a carburetor and which are well understood in the art.

In the drawings I show at 10 an accelerating well open to atmosphere at its upper end through a port 11 and communicating at its lower end with a fuel passage 12 that terminates in a fuel nozzle 13 discharging into venturi 14 of the mixture passage M of the carburetor. In the upper part of the mixture passage M is the usual throttle T, the upper end of the mixture passage being connectible to an engine in any known manner.

A well such as here shown will drop its fuel to such a level as shown at L¹ in Fig. 2

when throttle T is suddenly or widely opened. Then upon subsequent closure of the throttle to the position shown in Fig. 3, and consequent reduction of the depression at nozzle 13, the well will fill with fuel, but if of a size 55 large enough to function properly on some engines it will draw fuel from fuel passage 12 to such an extent as to so completely rob the idling mixture of fuel as to cause stoppage 60 of engine operation. In fact, such a well always has a tendency to draw fuel from the nozzle in filling.

In my invention the accelerating well is not fed with fuel directly from float chamber 15, but is fed through fuel port 16 from a fuel 65 passage 17 which also feeds the float chamber through a restricted port 18. At some convenient point in the structure the fuel passage 17 preferably has an upwardly extending leg 19, one wall of which has an overflow edge 20 adjacent the float chamber, the purposes of which will be described hereinafter.

In the float chamber 15 any suitable float, as the one shown at 21, may be employed to operate the fuel valve stem 22. This valve 70 stem seats at 23 on the fuel inlet 24 and controls flow of fuel from inlet 24 to fuel passage 17. From passage 17 the flow of fuel to the float chamber is restricted by port 18. Leakage to the float chamber around valve 75 stem 22 may be made very small.

When the carburetor is operating at low speed the conditions are substantially as shown in Fig. 1. The fuel level in float chamber 15, in vertical leg 19 and in accelerating 80 well 10, stands at level L, or substantially so. Fuel is being drawn up through fuel passage 12 and out through nozzle 13 into the mixture passage. If now the throttle is suddenly or 85 widely opened the depression at nozzle 13 is increased, fuel is drawn at a higher rate through that nozzle and therefore fuel is drawn from well 10, the rate of fuel flow through nozzle 13 being temporarily greater than the rate of flow through restricted fuel port 16. Thus the fuel level in accelerating 90 well 10 may fall to a point shown at L¹ in Fig. 2. Level L¹ is the limiting low level, as when 95 the fuel reaches that level air will begin to pass from the accelerating well along with 100

fuel into fuel passage 12 and thus more or less break the suction on the fuel passage. However in this condition the flow of fuel to nozzle 13 is not decreased, owing to the 5 additional effective fuel head on 16 due to the lowering of the fuel level in 10, and owing to the restriction of air flow through 11 and 27.

During the time of well discharge fuel has 10 been flowing through fuel port 16 into the accelerating well and thus to the fuel passage 12 and nozzle 13, so that during accelerating action the fuel nozzle draws normal or more than normal fuel from port 16 and also draws 15 additional accelerating fuel from the well. Thus, at the same time that fuel has been drawn from the well, the fuel level in float chamber 15 has necessarily fallen to such a level as indicated at L^2 in Fig. 2, as the fuel 20 that has been drawn through port 16 comes from passage 17 which is in communication with float chamber 15; and that fuel can only be replenished by an opening of valve 22 caused by lowering of float 21. The fuel during 25 accelerating action may flow from the float chamber to passage 17 and port 16 either through the restricted passage 18 or also through the check controlled passage 25. Normally the check valve 26 is closed, but during 30 any period of sudden increase in fuel requirement this check valve 26 may open as shown in Fig. 2 for flow of fuel from the float chamber to the fuel port 16. It may not in all cases be necessary to use the check controlled 35 fuel passage 25; but it is not objectionable in any case as it only allows free flow of fuel from float chamber 15 to passage 17 and port 16 whenever there is any abnormal demand for fuel.

40 At the end of any period of abnormal fuel requirement, as for instance when throttle T is again closed down as shown in Fig. 3, the fuel level in accelerating well 10 will still be low and the fuel level in float chamber 16 45 will also still be low, as at L^2 , and inlet 24 will be open. Check 26 prevents fuel from flowing from passage 17 to float chamber 15 through passage 25, limiting that flow of fuel to the restricted port 18. Consequently when 50 valve 22 is open a part of the fuel pressure from the fuel tank (the pressure under which the fuel is fed to fuel inlet 24) is imposed upon fuel passage 17 and the fuel level in vertical leg 19 immediately rises as is indicated in Fig. 3. The overflow edge 20 at the upper end of that leg limits the height to which the column of fuel may rise in 19, limits the pressure which may be brought to bear upon fuel port 16 leading to accelerating well 10, and also puts all excess fuel directly into the float chamber 15, the excess fuel merely overflowing the edge 20. The primary purpose of leg 19 is to limit the pressure which may be applied to port 16 as the fuel feed pressure is ordinarily greater than it is

desired to use. In cases where that fuel feed pressure is not too great the leg may either be extended high enough that there is no overflow, or the leg might be closed at its top or omitted altogether with the same result. In such a case the whole fuel feed pressure would be brought to bear on the ports 16 and 18—that is, the whole of the fuel feed pressure that is admitted to passage 17 by the opening of valve 22. But in practise it is best to use leg 19 to definitely limit the pressure and set a uniform maximum. As a result of this excess pressure brought to bear upon port 16 the accelerating well fills quickly and without drawing fuel from fuel passage 12 and nozzle 13. To aid in quick filling of the accelerating well a fuel passage may be provided also at 75 27 above the normal fuel level L in the accelerating well. Whenever fuel in 19 stands above passage 27 fuel will flow through that 80 passage into the accelerating well and help fill it quickly.

Port 18 is comparatively restricted in size so that, during the operation of filling the accelerating well fuel will not pass freely from 90 passage 17 to float chamber 15. The size of this passage is gauged so that the fuel level in the float chamber will rise to its normal at just about the time the accelerating well is filled to its normal level. And the relative 95 sizes of well 10 and leg 19 preferably are so fixed that the fuel in 19 drops to its normal level at about the same time that fuel reaches the normal level in 10.

100 Although the dimensions I will give are to be regarded in no manner as a restriction upon the invention, I may state certain typical and relative dimensions which will aid in a clear understanding of the operation of the device. Thus, for instance, nozzle 13 may be 105 $\frac{1}{8}$ inch in diameter; fuel port 16, $\frac{1}{16}$ inch in diameter; air bleed 11, $\frac{1}{16}$ inch in diameter; fuel passage 27, $\frac{1}{16}$ inch in diameter; fuel port 18, .040 inch in diameter and the checked fuel 110 passage 25, $\frac{1}{16}$ inch in diameter. The air opening at 30 into the upper part of the float chamber may be of any suitable size. The size of the air bleed at 11 together with the size of the air bleed at 27 have a part in controlling the rate at which the accelerating well empties, as they control the rate at which air enters the upper part of the accelerating well. With any given pressure upon fuel inlet 24, or at any given height of fuel column in vertical leg 19, and with any specific amount of reduction of the pressure on nozzle 13, the 115 rate at which the accelerating well fills depends primarily upon the relation between the sizes of the ports 16 and 18, and the relative sizes of these ports is determined in any particular carburetor to cause the accelerating well to fill in a suitably short time and before or by the time the excess pressure has 120 been taken off passage 17 by the closure of 125 130

valve 22 consequent upon the raising of the fuel level in the float chamber to normal.

I claim:

1. In combination with a carburetor having a mixture passage, a fuel chamber, a fuel inlet, a fuel inlet valve controlled by the fuel level in the fuel chamber, an accelerating well and a fuel nozzle fed from the accelerating well and discharging into the mixture passage; the combination of means for restrictedly feeding both the accelerating well and the fuel chamber independently of each other from the fuel inlet.

10 2. In combination with a carburetor having a mixture passage, a fuel chamber, a fuel inlet, a fuel inlet valve controlled by the fuel level in the fuel chamber, an accelerating well and a fuel nozzle fed from the accelerating well and discharging into the mixture passage; the combination of restricted passages leading from the fuel inlet respectively to the accelerating well and the fuel chamber.

15 3. In combination with a carburetor having a mixture passage, a fuel chamber, a fuel inlet to which fuel may be fed under pressure, an accelerating well and a fuel nozzle fed from the accelerating well and discharging into the mixture passage, fuel being delivered from said chamber to the mixture passage 20 only through the accelerating well; the combination of means controlled by the fuel level in the fuel chamber for applying fuel pressure from the fuel inlet to the accelerating well.

35 4. In combination with a carburetor having a mixture passage, a fuel chamber, a fuel inlet to which fuel may be fed under pressure, an accelerating well and a fuel nozzle fed from the accelerating well and discharging 40 into the mixture passage; the combination of means for applying restrictedly and independently to the accelerating well and fuel chamber at least a part of the fuel pressure at the inlet.

45 5. In combination with a carburetor having a mixture passage, a fuel chamber, a fuel inlet, a fuel inlet valve controlled by the fuel level in the fuel chamber, an accelerating well and a fuel nozzle fed from the accelerating well and discharging into the mixture passage; the combination of a fuel passage communicating with the fuel inlet under control 50 of said valve, an upward leg extension of the fuel passage having an overflow to the fuel chamber, and two restricted passages communicating between the fuel passage and the accelerating well and fuel chamber, respectively.

60 6. In combination with a carburetor having a mixture passage, a fuel chamber, a fuel inlet, a fuel inlet valve controlled by the fuel level in the fuel chamber, an accelerating well and a fuel nozzle fed from the accelerating well and discharging into the mixture passage; the combination of a fuel passage com-

municating with the fuel inlet under control of said valve, an upward leg extension of the fuel passage having an overflow to the fuel chamber, two restricted passages communicating between the fuel passage and the accelerating well and fuel chamber, respectively, and a checked passage adapted to pass fuel from the fuel chamber to the first mentioned fuel passage.

70 7. In combination with a carburetor having a mixture passage, a fuel chamber, a fuel inlet, a fuel inlet valve controlled by the fuel level in the fuel chamber, an accelerating well and a fuel nozzle fed from the accelerating well and discharging into the mixture passage; the combination of a fuel passage communicating with the fuel inlet under control of said valve, an upward leg extension of the fuel passage having an overflow to the fuel chamber, and two restricted passages communicating between the fuel passage and the accelerating well and fuel chamber, respectively, and a fuel opening adapted to pass fuel from the upper part of the leg into the accelerating well.

75 8. In combination with a carburetor having a mixture passage, a fuel chamber, a fuel inlet, a fuel inlet valve controlled by the fuel level in the fuel chamber, an accelerating well and a fuel nozzle fed from the accelerating well and discharging into the mixture passage; the combination of a fuel passage communicating with the fuel inlet under control of said valve, an upward leg extension of the fuel passage having an overflow to the fuel chamber, two restricted passages communicating between the fuel passage and the accelerating well and fuel chamber, respectively, and a fuel opening adapted to pass fuel from the upper part of the leg into the accelerating well, said opening being above the normal fuel level in the leg and well.

90 9. In combination with a carburetor having a mixture passage, a fuel chamber, a fuel inlet, a fuel inlet valve controlled by the fuel level in the fuel chamber, an accelerating well and a fuel nozzle fed from the accelerating well and discharging into the mixture passage; the combination of means for restrictedly passing fuel from the fuel inlet to the accelerating well and means for restrictedly passing fuel from the fuel inlet to the fuel chamber, the relative restrictions of said two means being so proportioned that the well will fill with fuel from said inlet during the time the fuel in the fuel chamber is rising to normal level.

95 10. In combination with a carburetor having a mixing passage, a fuel chamber, a fuel nozzle fed from the fuel chamber, and a fuel inlet to which fuel may be fed under pressure; the combination of means controlled by the fuel level in the fuel chamber for applying 100

fuel pressure from the fuel inlet to the fuel nozzle independently of the fuel chamber.

11. In combination with a carburetor having a mixing passage, a fuel chamber, a fuel nozzle fed from the fuel chamber, and a fuel inlet to which fuel may be fed under pressure; the combination of means for restrictedly feeding fuel from the fuel inlet to the fuel nozzle and the fuel chamber independently of each other.

In witness that I claim the foregoing I have hereunto subscribed my name this 9th day of August, 1926.
